UNITED STATES PATENT OFFICE.

ALEXANDER THOMAS FRASER, OF BUTTE, MONTANA,

DREDGE-BUCKET JOINT.

No. 878,517.

Specification of Letters Patent.

Patented Feb. 11, 1908.

Application filed May 23, 1907. Serial No. 375,328.

To all whom it may concern:

Be it known that I, ALEXANDER THOMAS FRASER, a citizen of the United States, and resident of Butte, Silverbow county, State of Montana, have invented certain new and useful Improvements in Dredge-Bucket Joints, of which the following is a specification.

The present invention relates to improvements in joints for dredge buckets, elevating and conveying apparatus, and similar structures including a series of links connected by hinge joints and has for its particular object to improve the form of joint illustrated and described in Patent 854,731 dated May 28, 1907.

The invention is illustrated in the accompanying drawing in which,

Figure 1 is an elevation and partial section through a portion of a dredge bucket and supporting chain, embodying the present invention; Fig. 2 is a horizontal sectional view on the line 2—2 of Fig. 1; Fig. 3 is a detail view.

Referring to the drawing it will be seen that the bucket 1 is connected with a chain composed of links, each having at one end a tubular bar 3 and having its opposite end bifurcated to provide two arms or lugs 4 separated sufficiently to receive the lug 3 of an adjacent link, said lugs 3, 4, being connected by bolts or pivot pins 5.

As is well understood means must be provided for preventing the pin 5 from turning relative to the lugs 4 because if such turning is permitted the lugs would be rapidly worn away by grit, etc., which necessarily finds lodgment in the joints.

According to the present invention the pin 5 is held from turning in the lugs 4 by blocks 6, each having a curved face adapted to partly surround and fit closely against the pin. Said blocks are held in place in the lugs 4 and pressed against the pins 5 by wedges 7.

Each of the blocks 6 is provided on opposite faces with lugs 8 which enter seats or recesses in opposite sides of the slots in the lugs 4 in which each of said blocks extend and by means of said lugs 8 the blocks and lugs 4 are so connected that movement of the blocks longitudinally of the pins 5 is prevented.

The blocks 6 are so constructed that the projecting ends of the curved surface thereof and the ends of the lugs 8 are all included within a circle having a diameter equal to that of the passage for the pin 5, so that said

blocks may be readily inserted in the lugs and then moved longitudinally of the links to properly seat said lugs 8 in the sockets provided for them.

It will be understood that the sockets or recesses for the lugs 8 do not extend through the side faces of the lugs 4 and that the opening in such side faces of the lugs is merely of a width sufficient to accommodate the body 60 of the block 6.

After the pins 5 have been inserted the wedges 7 are driven between the ends of the blocks and the body of the lug, thus locking the pins firmly to the lugs.

By referring to Fig. 2 it will be seen that while the wedges 7 extend entirely through the lugs 4 they are so arranged as to be out of contact with the lug 3 of the adjacent link and can be readily driven from engaging 70 position when desired.

By employing a locking means of the character illustrated and above described, the lugs 4 are not weakened and the structure presents some practical advantages 80 over the form of lock shown in the application hereinbefore referred to.

Having described my invention what I claim and desire to secure by Letters Patent is:

1. In a chain of the character described, the combination with links having lugs, and pivot pins connecting lugs of adjacent links, of means for locking the pins to certain of said lugs comprising blocks seated in said 90 lugs and bearing on the pins, and wedges extending substantially parallel with said pivot pins and bearing on said blocks.

2. In a chain of the character described, the combination with links having lugs, and 95 pivot pins connecting lugs of adjacent links, of means for locking the pins to certain of said lugs comprising blocks seated in said, lugs and each having a curved face adapted to bear on a pivot pin and having on opposite sides of its body projections adapted to engage the link lugs and prevent movement of said blocks longitudinally of the pivot pins, and wedges operating to hold said blocks in 100 contact with the pivot pins.

3. In a chain of the character described, the combination with links each having a pair of separated lugs at one end adapted to receive between them a member of an adjacent link, and pivot pins each extending 110 through the separated lugs of one link and the intermediate member of another link, of

means for locking the pins to said separated lugs, comprising a block seated in each of said lugs and bearing on the pivot pins, and wedges extending through said lugs in the direction of the length of the pivot pin and holding said blocks against the pivot pin.

4. In a chain of the character described, the combination with links each having a pair of separated lugs at one end adapted to 10 receive between them a member of an adjacent link, and pivot pins each extending through the separated lugs of one link and the intermediate member of another link, of means for locking the pins to said separated 15 lugs, comprising a block seated in each of said lugs and bearing on the pivot pins, and wedges extending through said lugs in the direction of the length of the pivot pin and in rear of the member of the other link and 20 holding said blocks against the pivot pin.

5. In a chain of the character described, the combination with links having lugs, and pivot pins connecting lugs of adjacent links, of blocks fitted in seats formed in the lugs of

one link and bearing against the pivot pin 25 extending into said lugs, means engaging said block to prevent movement thereof longitudinally of the pivot pin, and wedges extending through the lugs in which the blocks are mounted and holding the blocks 30 against the pivot pin.

6. The combination of a chain link having at one end a pair of separated lugs, a second link having a lug extending between the lugs on the first said link, a pivot pin extending 35 through passages in the said lugs of both links, blocks fitted in seats in the lugs of the first said link and bearing on the pivot pin, and wedges extending longitudinally of the pivot pin through the lugs of the first said link at 40 one side of the intermediate lug of the second said link and engaging said blocks.

In testimony whereof I affix my signature in presence of two witnesses.

ALEXANDER THOMAS FRASER.
